UNITED STATES PATENT OFFICE

BRANCH HEATH, OF TORONTO, ONTARIO, CANADA, ASSIGNOR TO CANADA CYCLE & MOTOR CO. LIMITED, OF WESTON, ONTARIO, CANADA

PROTECTOR FOR SKATE BLADES

Application filed February 16, 1929. Serial No. 340,537.

The principal objects of the invention are to provide a simple and effective means for preventing injury to persons coming in contact with the ends of ice skates and to devise 5 a guard which will not detract from the appearance of the skate or render it cumbersome in any way.

A further and important object is to devise a form of guard which may be applied 10 to skates already manufactured or in use, or which may be applied to skates in their course of manufacture.

The principal feature of the invention consists in the novel arrangement of a globular-shaped guard member adjacent to the point 15 of the skate blade to protect and guard any object coming in contact with the ends of the skate from being cut by the point of the blade.

20 In the drawing, Figure 1 is a side elevational view of a skate showing my improved protector attached thereto.

Figure 2 is a perspective detail of the attachable form of guard, as shown in Figure 1. 25 Figure 3 is a longitudinal and enlarged sectional view of the guard shown in Figure 1.

Figure 4 is an enlarged perspective detail of the rear end of a tube skate showing the 30 arrangement of a globular protector formed as a part of the skate construction.

Figure 5 is a view similar to Figure 4 of the toe end.

Figure 6 is a cross-sectional view through 35 the toe end protector shown in Figure 5, taken on the line 6—6.

The increasing use of the tube form of skate with a long projecting toe and heel portion has, on account of numerous painful 40 accidents through persons falling against these skates, necessitated the use of a guard and toe guards have been applied extending forwardly from the toe end of the sole plate to meet the point of the blade. These are 45 clumsy both in appearance and in use and they do not guard the heels. It has, therefore, become necessary to provide some form of guard which will extend close to the point of both heel and toe which will prevent persons being cut thereby.

The present invention has accomplished a very desirable way of protecting the blade and it comprises a globular-shaped member 50 preferably formed up of sheet metal and provided with a slot to receive the edge of the blade and with flanges to be secured to the blade.

In the form shown in Figures 1, 2 and 3 a small sheet metal stamping is formed with a spherical end 1 comprising two hemisphere 60 portions which are connected together by the doubled flanged portion 2. This flanged portion is provided with an offset portion 3 adjacent to the notch 4 in the underside of the sphere.

The notch 4 is squared at the end 5 to abut the edge of the blade 6 of the skate at a point slightly above the point of the blade 7 at the rear end and the offset portions 3 of the member 2 overlap the flange portion 8 70 of the skate tube top while the narrower portion 2 fits snugly over the portion 9 which extends from the tube 10.

A couple of rivets 11 are inserted through the portions 2 of the guard and through the 75 portion 9 of the skate tube. These secure the protector firmly in place and guard the rear point of the blade.

The form shown in Figure 3 is slightly 80 different but only in regard to the shape and arrangement of the overlapping flange portions 12, the ball end 1 being the same. The doubled flanges 12 fit over the forward end of the blade and the forward end of the flanges 8 of the skate tube and rivets 11' 85 secure the member in place with the ball substantially even with the point 7' of the skate.

In the forms of the invention illustrated in Figures 4, 5 and 6, the thin sheet metal structure of the tube 10 is pressed up with a 90 globular or spherical form 13 at the rear end and a similar spherical form 14 at the front end. These are pressed up in half sections when the tube is pressed in the flat and when it is formed over into the tube shape, 95 the half sections are brought together to embrace the point of the toe end of the skate and to close around the heel portion slightly.

It will be seen that a protector such as described is extremely simple in form, the 100

weight is insignificant and when stamped up as part of the tube it adds nothing to the cost of manufacture of the skate.

The device when formed up as shown in Figures 2 and 3 is easily applied and the cost is extremely low.

What I claim as my invention is:

1. In a skate, a hollow globular formation arranged adjacent to the point of the blade and forming a guard, said globular formation presenting continuous unbroken side and forward surfaces.
2. A guard for skate blades, comprising a member having a channeled portion embracing the blade and having a hollow globular-shaped extension projecting over said blade adjacent to and above the point.
3. A protector for skate blades, comprising a thin sheet metal member stamped into a globular form having depending side portions extending therefrom and embracing the upper edge of the blade and secured thereto.
4. A protector for skate blades, comprising a thin sheet metal member stamped with semi-globular projections and folded together, having flange portions adapted to engage and be secured to the blade of the skate.
5. A protector for skate blades, comprising a thin sheet metal member bent into substantially U-shaped form adapted to embrace the edge of the skate blade and having a globular formation at the end adapted to fit over the skate blade adjacent to the points.
6. In a skate, a globular guard member arranged at the end extremity of the blade and supported thereby from the inward side, said globular guard member presenting unbroken side and forward surfaces.

BRANCH HEATH.
